UNITED STATES PATENT OFFICE

171,076

SPOON OR SIMILAR ARTICLE OF FLATWARE

Milton Bernstein, New York, N. Y.

Application February 18, 1953, Serial No. 23,682

Term of patent 14 years

(Cl. D54—12)

To all whom it may concern:

Be it known that I, Milton Bernstein, a citizen of the United States, residing in the city of New York, county of New York, State of New York, have invented a new, original, and ornamental Design for a Spoon or Similar Article of Flatware, of which the following is a specification, reference being had to the accompanying drawing, forming a part hereof, in which:

Fig. 1 is a plan view of a spoon or similar article of flatware embodying my new design.

Fig. 2 is a side elevational view of the spoon.

The back of the article is conventionally plain.

I claim:

The ornamental design for a spoon or similar article of flatware, as shown and described.

MILTON BERNSTEIN.
